STRUCTURAL FLOOR

Lewis Inglee, Amityville, N. Y.

Application April 28, 1930. Serial No. 447,964

8 Claims. (Cl. 72—66)

My invention relates to structural floors and ceilings and refers particularly to fireproof floors and ceilings.

The usual method employed for the production of hollow fireproof floors and ceilings is to erect a metallic skeleton to form the hollow spaces, erect a temporary, or false, ceiling to support the plastic material until it has set, or hardened, and then remove the temporary ceiling.

10 There is considerable expense in material and time incident to the erection and removal of this false, or temporary ceiling, and delay is occasioned in the erection of the permanent ceiling as the temporary ceiling can not be removed until the plastic material has set.

My invention overcomes the above mentioned, and other, objectionable features incident to the present employed methods of floor construction, as it obviates the necessity of temporary, or false, 20 ceilings and allows of the erection of the permanent ceiling prior to the absolute hardening of the plastic material employed.

The several valuable features of the device of my invention will be evident upon a consideration 25 of my specification and accompanying drawings.

In the accompanying drawings showing modified forms of the device of my invention, similar parts are designated by similar numerals.

Figure 1 is a perspective view of one form of 30 the device of my invention.

Figure 2 is a perspective view of a modified form of the device of my invention.

Figure 3 is a perspective view of a modified form of the device of my invention.

35 Figure 4 is a perspective view of a modified form of the device of my invention.

Figure 5 is a perspective view of the tin pan shown in the drawings.

40 Figure 6 is an enlarged perspective view of the sleeper support of Figure 1.

Figure 7 is a section through the line 7—7 of Figure 6.

45 Figure 8 is a perspective view of a modified form of the device of Figure 6.

Figure 9 is an enlarged perspective view of the sleeper support of Figure 2.

Figure 10 is a section through the line 10—10 of Figure 9.

50 Figure 11 is an enlarged perspective view of the suspended hook of Figure 1.

Figure 12 is an enlarged perspective view of the suspending hook of Figure 2.

55 Figure 13 is an enlarged perspective view of the suspending plate of Figure 3.

Figure 14 is a section through the line 14—14 of Figure 13.

Figure 15 is a perspective view of a modified form of the device of Figure 13.

The particular construction shown in Figures 1, 5, 6, 7 and 11 comprises a plurality of parallel spaced I beams 20, 20. A plurality of hooks 21, 21, are suspended from the lower flange of each beam and a plurality of transverse parallel rods 22, 22, are supported by said hooks 21, 21. Wire 60 lath 23, 23, is then laid upon the rods 22, 22 and supported thereby. A plurality of inverted elongated tin pans 24, 24, are then positioned upon the wire lath 23, 23, between the I beams. The flanges 25, 25, of the tin pans have a plurality 70 of openings 26, 26, and their up-turned ends 27, 27, are clamped together by means of the clamps 28, 28. The upper flanges of the I beams carry a plurality of upwardly extended supports 29, 29, having a plurality of openings 30, 30, therein. 75 Supported by the supports 29, 29, of each I beam and spaced from the bottom thereof is a sleeper 31. It will thus be seen that the entire construction thus formed is supported by the I beams and that it has been erected without the necessity 80 of a temporary flooring. Concrete, or other desirable material, 100 is then poured in, which passes through the openings 26, 26, and the openings 30, 30, thus forming a solid concrete mass, completely covering the I beams, the upper faces 85 of the tin pans, and the sleepers with the exception of their upper faces. The upper face of the concrete can then be levelled and the flooring 32 laid, and the ceiling 33 plastered.

The modified form of construction shown in Figures 2, 5, 9, 10 and 12 comprises a plurality of spaced parallel bar joists 34, 34. The lower bar joists 34, 34, carry a plurality of suspended hooks 35, 35, carrying the rods 22, 22, the metal lath 23, 23 and the tin pans 24 as previously described. 95 The upper bar joists carry a plurality of upwardly extended supports 36, 36, each having a plurality of openings 37, 37, therein. Supported by each set of upwardly extended supports 36, 36, is a sleeper 38. Concrete, or other suitable material, 100 100 is poured into the device thus constructed until it reaches the lower faces of the sleepers 38, 38. The flooring 39 and the ceiling 40 are then introduced. In this construction there is an air space 41, between the flooring 39 and the upper face of the cement 100.

The modified form of construction shown in Figures 3, 5, 13 and 14 comprises a plurality of spaced parallel I beams 42, 42. The lower flanges of each I beam carry a plurality of suspended 110

plates 43, 43, having a plurality of openings 44, 44, therein. A plurality of spaced parallel rods 45, 45, are passed through openings 44, 44, of the plates 43, 43. In order to prevent accidental movement of the rods 45, 45, they are notched, a cut out portion 43 of the plate 43' being positioned in a rod notch. Attached to the suspending plates 43, 43, of each I beam 42 is a sleeper 46. Wall boards 47, 47, are attached to the lower faces of the sleepers 46, 46, by means of the finish trims 48, 48, which can be done either before or after the concrete 100 is poured. Concrete, or other desirable material, 100 is then poured until it reaches a height above the top flanges of the I beams 42, 42, and a concrete, or other suitable flooring, 49 is laid.

The modified form of construction shown in Figure 4, is similar to that shown in Figure 3 except that it contains a plurality of reinforcing rods 50, 50, carried by the upper flanges of the I beams 42, and insulating board 51, 51, is carried by the rods 45, 45, and a plaster ceiling 52 is applied.

The form of support shown in Figure 8 is a modification of that shown in Figure 6, the latter being constructed to support a sleeper parallel to the I beam while that shown in the figure is constructed to support a sleeper at right angles to the beam.

30 The form of suspending hook shown in Figure 15 is a modification of that shown in Figure 13, the latter being adapted for use with I beams while that shown in this figure is adapted for employment with bar joists 53.

35 It will thus be seen that in the construction of floors of my invention, the tin pan, or mold, is supported by supporting means extending from joist to joist and that at no time is it necessary to erect a temporary, or false, ceiling, and, further, that the permanent ceiling may be constructed without waiting for the plastic material to be absolutely hard, or set.

40 It will be further noted, that my invention allows of a floor construction capable of adaptation to various shapes and character of metal skeletons, molds, and joists.

I do not limit myself to the particular size, shape, number, form, arrangement or material of parts as shown and described as these are given simply as a means for clearly explaining my invention.

What I claim is:—

1. In a structural floor, in combination, a plurality of spaced parallel fixed joists, suspended carrying members carried by each said joist, a plurality of supporting members carried by said carrying members suspended from adjacent joists, an inverted trough-shaped member positioned between adjacent joists and supported by said supporting members, a perforated sleeper support carried by the upper portion of each said joist, a sleeper carried by each sleeper support and plastic material covering the upper surface of said trough-shaped member and surrounding said joists.

2. In a structural floor, in combination, a plurality of spaced parallel fixed joists suspended carrying member carried by each said joist, a plurality of supporting members carried by said carrying members suspended from adjacent joists, an inverted trough-shaped member positioned between adjacent joists and supported by said supporting members, the flanges of said trough-shaped members being perforated, means capable of fastening adjacent trough-shaped

members with respect to each other, and plastic material covering the upper surface of said trough-shaped member and surrounding said joists.

3. In a structural floor, in combination, a plurality of spaced parallel fixed joists, suspended carrying members carried by each said joist, a plurality of supporting members carried by said carrying members suspended from adjacent joists, an inverted trough-shaped member positioned between adjacent joists and supported by said supporting members, the flanges of said trough-shaped members being perforated, means capable of fastening adjacent trough-shaped members with respect to each other, a perforated sleeper support carried by the upper portion of each said joist, a sleeper carried by each said sleeper support, and plastic material covering the upper surface of said trough-shaped member and surrounding said joists. 95

4. In a structural floor, in combination, a plurality of spaced parallel fixed joists, suspended carrying members carried by each said joist, a plurality of supporting members carried by said carrying members suspended from adjacent joists, an inverted trough-shaped member positioned between adjacent joists and supported by said supporting members, a perforated sleeper support carried by the upper portion of each said joist, a sleeper carried by each said sleeper support, plastic material covering the upper surface of said trough-shaped member and surrounding said joists and a ceiling carried by the under portion of the structure thus formed. 105

5. In a structural floor, in combination, a plurality of spaced parallel fixed joists, suspended carrying members carried by each said joist, a plurality of supporting members carried by said carrying members suspended from adjacent joists, an inverted trough-shaped member positioned between adjacent joists and supported by said supporting members, the flanges of said trough-shaped members being perforated, means capable of fastening adjacent trough-shaped members with respect to each other, a perforated sleeper support carried by the upper portion of each said joist, a sleeper carried by each said sleeper support, plastic material covering the upper surface of said trough-shaped member and surrounding said joists and a ceiling carried by the under portion of the structure thus formed. 110

6. In a structural floor, in combination, a plurality of spaced parallel fixed joists, suspended carrying members carried by each said joist, a plurality of supporting members carried by said carrying members suspended from adjacent joists, a ceiling support carried by said supporting members, an inverted trough-shaped member positioned between adjacent joists and supported by said supporting members, the flanges of said trough-shaped members being perforated, means capable of fastening adjacent trough-shaped members with respect to each other, plastic material covering the upper surface of said trough-shaped member and surrounding said joists and a ceiling carried by said ceiling support. 130

7. In a structural floor, in combination, a plurality of spaced parallel fixed joists, suspended carrying members carried by each said joist, a plurality of supporting members carried by said carrying members suspended from adjacent joists, a ceiling support carried by said supporting members, an inverted trough-shaped member positioned between adjacent joists and sup- 145

ported by said supporting members, a perforated sleeper support carried by the upper portion of each said joist, a sleeper carried by each sleeper support, a plastic material covering the upper surface of said trough-shaped member and surrounding said joists and a ceiling carried by said ceiling support.

8. In a structural floor, in combination, a plurality of spaced parallel fixed joists, suspended carrying members carried by each said joist, a plurality of supporting members carried by said carrying members suspended from adjacent joists, a ceiling support carried by said support-

ing members, an inverted trough-shaped member positioned between adjacent joists and supported by said supporting members, the flanges of said trough-shaped members being perforated, means capable of fastening adjacent trough-shaped members with respect to each other, a perforated sleeper support carried by the upper portion of each said joist, a sleeper carried by each said sleeper support, plastic material covering the upper surface of said trough-shaped member and surrounding said joists and a ceiling carried by said ceiling support.
